UNITED STATES PATENT OFFICE.

WILLIAM EDWARD CALLISON, OF TULSA, OKLAHOMA.

AMUSEMENT DEVICE.

Application filed July 12, 1927. Serial No. 205,158.

My invention relates to an improvement in amusement devices of the type of aerial projectile targets with ball return and is particularly adapted for use with the amusement device of the patent to W. A. Tratsch, dated September 1, 1925, No. 1,551,858, in which a coin-controlled pistol may be caused to propel a ball to a target in which the balls, after striking the target, roll down an inclined plane into place to be loaded into the pistol when the reloading device has been released by a coin inserted in the coin slot, and in which the reloading of the pistol operates a device for resetting any target indicator which has been caused to be shown.

My invention has for its object to provide a stop device in the path of the balls as they roll back from the target so as to permit them to be counted before being returned to the pistol and to so arrange the stop device that movement of the reloading device by which the targets are reset operates to lift the stop device and release the balls retained by it. A further object of the invention is the provision in the stopping device of pockets which may be numbered so that the lodging of a ball in one pocket rather than another as well as hitting the bull's eye of a target may require the exercise of special skill.

With the objects above indicated, and other objects hereinafter explained in view my invention consists in the construction and combination of elements hereinafter described and claimed.

Referring to the drawings:

Figure 1 is a top plan view of an amusement device embodying my invention.

Figure 2 is a vertical longitudinal central 40 sectional view of the device shown in Figure 1.

Figure 3 is a perspective view of the stopping bar.

In the drawings 1 indicates the box in which the targets 2 and return runway 3 are located beneath a sheet of glass 4. 5 indicates the pistol of the patent to Tratsch, above referred to, mounted to swing on a vertical pivot and also on a horizontal pivot 50 so as to be capable of being aimed and having on one side a coin slot 6 and a slide 7 which being pushed forward after a coin has been inserted in the coin slot reloads the pistol with the balls which have been previously propelled from the pistol.

With this slide 7 is connected a rod 8

which extends forward to the targets for the purpose of resetting any indicators which have been struck. This rod and the construction of the target indicator resetting means form no part of my present invention.

On the inclined plate 9 which forms the runway for returning the balls after they have been propelled to the targets, I arrange a stop device consisting of a bar 10 extending across the runway with its ends 11 and 12 extending towards the targets. These arms 11 and 12 are pivoted at their ends to the sides of the enclosing box 1. Midway between its ends bar 10 is provided with a pin 13 which extends downward through an opening 14 in inclined plate 9 in position to be struck and forced upward by a cam 15 secured on rod 8.

The initial forward movement of slide 7 moves rod 8 and cam 15 forward far enough to cause the cam to act against the lower end of pin 13 so as to swing bar 10 upward on the pivots of arms 11 and 12 sufficiently to permit any balls which may have been stopped by it to roll under it and to roll down into position to be reloaded into the pistol.

The stopping bar 10 is preferably provided with fingers 16 extending towards the targets so arranged as to leave between each two adjacent fingers a pocket 17. These pockets may be numbered so as to serve as targets for ricochet target practice.

The pistol is arranged to shoot three or five or any other number of balls. The stopping device shows the number of balls shot and thus serves as a check on any claim by a user that he has not been able to shoot the number of balls paid for.

Having thus described my invention, what I claim is:

1. In an amusement device having a propelling device for balls, a target above the level of the propelling device and an inclined surface leading from the target to the propelling device for returning the balls thereto, means between the target and the propelling device for stopping the balls as they return from the target and means for lifting the stopping means to release the balls stopped by it.

2. In an amusement device having a propelling device for balls, a target above the level of the propelling device, and an inclined surface leading from the target to the propelling device for returning the balls

thereto, means between the target and the propelling device for stopping the balls as they return from the target comprising a bar extending across the inclined surface 5 having arms extending towards the target pivoted at the ends of the arms and means for swinging the bar upward upon its pivots to release the balls.

3. In an amusement device having a propelling device for balls a target above the 10 level of the propelling device, and an inclined surface leading from the target to the propelling device for returning the balls thereto and means for reloading the propelling device, means between the target and the propelling device for stopping the balls 15 as they return from the target comprising a bar extending across the inclined surface having arms extending toward the target 20 pivoted at the ends of the arms and means operated by the reloading means for swinging the bar upward on its pivots to release the balls stopped by it.

4. In an amusement device having a propelling device for balls a target above the 25 level of the propelling device, and an inclined surface leading from the target to the propelling device for returning the balls thereto and a slide for reloading the propelling device, means between the target and the propelling device for stopping the balls 30 as they return from the target comprising a bar extending across the inclined surface and means operated by the reloading slide for 35 lifting the bar upward to release the balls stopped by it comprising a rod connected with the reloading slide extending toward the target and means carried by the rod for lifting the bar to release the balls stopped 40 by it.

5. In an amusement device having a propelling device for balls, a target above the

level of the propelling device, and an inclined surface leading from the target to the propelling device for returning the balls 45 thereto, a slide for reloading the propelling device, means between the target and the propelling device for stopping the balls as they return from the target comprising a bar extending across the inclined surface 50 having arms extending towards the target pivoted at the ends of the arms and means operated by the reloading means for swinging the bar upward on its pivots to release the balls stopped by it comprising a rod 55 connected with the reloading slide extending toward the target and means carried by the rod for swinging the bar upward on its pivots to release the balls stopped by it.

6. In an amusement device having a propelling device for balls, a target above the 60 level of the propelling device, and an inclined surface leading from the target to the propelling device for returning the balls thereto, means between the target and the 65 propelling device for stopping the balls as they return from the target comprising a bar extending across the inclined surface provided with pockets to receive the balls.

7. In an amusement device having a propelling device for balls, a target above the 70 level of the propelling device, and an inclined surface leading from the target to the propelling device for returning the balls thereto, means between the target and the 75 propelling device for stopping the balls as they return from the target comprising a bar extending across the inclined surface provided with pockets to receive the balls, and means for lifting the bar to release any balls in the pockets.

In testimony whereof, I hereunto affix my signature.

WILLIAM EDWARD CALLISON.
